DESIGN FOR A BOTTLE

Edwin T. Reynolds, West New York, N. J., assignor to Lorr Laboratories, Inc., West New York, N. J., a corporation of New Jersey

Application December 21, 1936, Serial No. 66,667

Term of patent 14 years

To all whom it may concern:

Be it known that I, Edwin T. Reynolds, a citizen of the United States, residing at West New York, in the county of Hudson and State of New Jersey, have invented a new, original, and ornamental Design for a Bottle, of which the following is a specification, reference being had to the accompanying drawing, forming part thereof.

I claim:

The ornamental design for a bottle, as shown.

EDWIN T. REYNOLDS.
